A. MORRISON.

TIE PLATE.

APPLICATION FILED JUNE 11, 1920.

1,348,370.

Patented Aug. 3, 1920.

UNITED STATES PATENT OFFICE.

ANDREW MORRISON, OF PITTSBURGH, PENNSYLVANIA, ASSIGNOR TO DILWORTH-
PORTER & COMPANY, INCORPORATED, OF PITTSBURGH, PENNSYLVANIA, A
CORPORATION OF PENNSYLVANIA.

TIE-PLATE.

1,348,370.

Specification of Letters-Patent.

Patented Aug. 3, 1920.

Application filed June 11, 1920. Serial No. 388,105.

To all whom it may concern:

Be it known that I, ANDREW MORRISON, a citizen of the United States, residing at Pittsburgh, Allegheny county, Pennsylvania, have invented a new and useful Improvement in Tie-Plates, of which the following is a full, clear, and exact description, reference being had to the accompanying drawings, forming part of this specification.

10 The present invention relates particularly to tie plates for railroads.

The principal object of the invention is to provide a tie plate in which all of the bearing surfaces, including the rail tread 15 and the upper surface of the tie plate, are normal to the downward thrust produced by the wheel load, and in which the lower surface of the tie plate is so shaped that a maximum resistance to lateral outward 20 creeping of the tie plate, which would ordinarily be caused by the lateral wheel thrust and resultant wheel thrust, is afforded without cutting of the tie fibers.

A further object of the invention is to 25 provide a tie plate of the construction described in which the plate is cambered in a direction parallel to the direction of extension of the rail which is placed thereon, to prevent movement of the tie plate with 30 the rail.

The foregoing and other objects, together with their attendant advantages, will be apparent as the invention becomes better understood, by reference to the accompanying 35 specification and drawings forming a part thereof, it being premised that changes may be made in the various details and the manner of operation, within the scope of the appended claims, without departing 40 from the spirit of the invention.

Figure 1 is a transverse section through a tie plate and rail, showing a portion of a standard coned tread car-wheel.

Fig. 2 is a side elevation of a tie plate 45 and rail section, showing a portion of a tie in section.

Fig. 3 is a perspective view of the improved tie plate, and

Fig. 4 is a diagrammatic illustration of 50 the influences with special reference to which the tie plate is designed.

I am aware that it is old to construct railway tie plates having a relatively thin entrance edge and a thickened anvil portion

remote therefrom, with pointed cutting 55 teeth directed toward said anvil portion, and that it is also old to construct invertible tie plates having projecting cutting ribs on opposite sides adjacent the opposite edges thereof, but such constructions have not 60 been successful due largely to the cutting action on the tie fibers. I am also familiar with rail joints adapted to rest at their end portions upon adjacent ties and having a series of serrations or shoulders adapted 65 to enter the material of which the ties are composed, but my invention has no relation to such constructions.

It has also been proposed to provide tie plates with ribs at an oblique angle, and to 70 provide tapered tie plates having on their lower face a number of projecting spurs adapted to embed themselves in the tie by a cutting action which the present invention overcomes.

75 The general problems involved in tie plate constructions, and successfully overcome by this invention, have been recognized and an unsuccessful attempt has been made to overcome the same by constructing a cambered tie plate having an upper rail seat normal to the line of thrust of the standard coned tread car-wheel, and lower stepped surfaces parallel with said seat, but stepped surfaces so arranged have assisted and not 80 prevented lateral creeping.

85 Referring more particularly to the drawings, there is illustrated a tie plate 2 provided with a rail abutting shoulder 3 adjacent one end thereof, and with the usual spike openings 4 to assist in holding the tie plate in position. The main body of the tie plate is cambered transversely in a direction parallel to the direction of extension 90 of a rail 5 placed thereon. This camber 95 provides opposite side edges 6 which are lower than the main body of the tie plate and which embed themselves firmly in the tie to prevent longitudinal creeping of the tie plate.

100 According to the present invention, the main body of the tie plate is slightly tapered to provide a thickened portion adjacent the shoulder 3 and a relatively thin inwardly projecting portion. This taper is 105 calculated in such manner that the upper rail seat 7 will be normal to the downward thrust of a standard coned tread car wheel,

such as illustrated in dotted lines in Fig. 1, and producing a wheel load stress in the direction of the inclined line *a*—*b*. In Fig. 4, this stress is indicated by the arrow *A* designated "wheel load." In addition to this stress, there is a laterally acting stress indicated in Fig. 4 by the arrow *B* designated "wheel thrust." These two stresses, which are acting during the passing of a car over the rails, produce a third stress indicated by the arrow *C* and designated "resultant wheel thrust." It will be apparent that all of these stresses combine to produce a "spread" of the rails and tie plates as represented by the arrow *D*. This tendency to spread is increased by the taper of the tie plate and the tendency thereof to creep from under a load which is not effective thereon or transmitted thereto in a true vertical plane.

The present invention overcomes this spreading tendency by forming the lower surface of the tie plate with a series of wide bearing surfaces 8 oppositely inclined with respect to the upper rail seat, the inclination in this instance being upwardly and inwardly. These bearing surfaces 8 are connected by abruptly upwardly and outwardly inclined portions 9. The high points 10 of these abruptly inclined portions are rounded or convex to form non-cutting projections which while effective for displacing the tie fibers downwardly do not exert any cutting action thereon. These portions present shoulders to the ties which are effective for preventing outward lateral creeping or displacement of the tie plates. In Fig. 4 the arrow *E* marked "resistance" illustrates the direction in which these shoulders are effective. It is essential that these shoulders be abrupt as a gradual inclination assists the "resultant wheel thrust" and increases the lateral outward creeping of the tie plates, thereby permitting an undue spreading action. With the present construction, the "resistance" is effective in direct opposition to the "resultant wheel thrust," thereby preventing any spreading or creeping.

50 The camber transversely of the tie plate

coöperates with the particular construction of the under surface of the tie plate to prevent any objectionable movement thereof.

The advantages of the present invention arise from the non-cutting tie plate provided which presents surfaces normal to the downward line of stress of a standard coned tread car-wheel and which maintains itself in fixed relation to the tie, both laterally and longitudinally.

I claim:

1. A tie-plate for railway rails having an upper rail seat normal to the line of thrust of the standard coned tread car-wheel and having a series of wide lower bearing surfaces upwardly and inwardly inclined at an oblique angle to the rail seat, said upwardly inclined surfaces being connected by abruptly upwardly and outwardly extending surfaces, said surfaces being gradually merged into each other by convex rounded portions forming anti-cutting edges, substantially as described.

2. A cambered tie plate for railway rails having an inclined upper rail seat normal to the line of thrust of the standard coned tread car-wheel and a lower tie-engaging surface comprising a series of wide bearing surfaces oppositely inclined with respect to said seat, said inclination being gradual upwardly and inwardly, and abruptly upwardly and outwardly inclined portions having their high points rounded and forming shoulders connecting said bearing surfaces, substantially as described.

3. A tie plate for railway rails having an inclined upper rail seat normal to the line of thrust of the standard coned tread car-wheel, and a lower tie-engaging surface comprising a series of wide bearing surfaces across the entire width thereof and oppositely inclined with respect to said seat, said inclination being gradual upwardly and inwardly, and abruptly upwardly and outwardly inclined portions forming shoulders for connecting said bearing surfaces, substantially as described.

In testimony whereof I have hereunto set my hand.

ANDREW MORRISON.
